UNITED STATES PATENT OFFICE.

HARVEY ISERMAN, OF NEW HYDE PARK, NEW YORK, ASSIGNOR TO MULTIPLE-GRAVE-BAR ENDLESS CHAIN STOKER COMPANY, A CORPORATION OF NEW YORK.

FURNACE.

1,125,543.

Specification of Letters Patent.

Patented Jan. 19, 1915.

Original application filed September 11, 1911, Serial No. 648,745. Divided and this application filed November 7, 1911. Serial No. 658,926.

To all whom it may concern:

Be it known that I, HARVEY ISERMAN, a citizen of the United States, residing at New Hyde Park, in the county of Nassau and State of New York, have invented a certain new and useful Improvement in Furnaces, of which the following is a full, clear, and exact description.

My invention is an improvement in furnaces and, while of general applicability, it is especially adapted for use in furnaces where mechanical stokers of the endless traveling grate type are employed.

The object of my invention is to provide a furnace having an ignition arch under which the first stages of combustion shall take place, and which arch shall be at the same distance above the flat horizontal grate at all points of its breadth, and to so construct the furnace front that no horizontal thrust shall be exerted against the side walls. I accomplish these results by supporting the furnace front and that part of the weight of the boiler and its contents which said furnace front receives, on structural iron or steel beams resting on the side walls and protect these beams from the fire by fire-brick blocks carried on doors which are mounted to swing under the said beams. The fire-brick blocks mounted as above described, form the flat ignition arch when the doors are in closed position.

A further object of my invention is to so construct the ignition arch and to so locate it with relation to other coöperating parts to be later described as to provide more complete and efficient combustion of the fuel than has hitherto been obtained.

This application is a division of my prior application Serial Number 648,745, filed September 11th, 1911.

In the drawings, Figure 1 is a central, vertical cross-section of the front of a boiler and furnace embodying my invention, the boiler and grate bars being shown in elevation for sake of clearness in the drawings; Fig. 2 is a partial front view of the furnace shown in Fig. 1, the fuel hopper being removed and one of the doors being open to show its construction; and Fig. 3 is a perspective of the special fire-brick lining for the doors.

As shown in the drawing, 3 is a steam

boiler mounted in the usual furnace structure which has side walls 4 and the front 55 wall 5. The front of the furnace is covered by a metal plate 6 which extends down over the side walls, forming a covering therefor and a means of mounting the doors, hopper, side plates and other parts of the mechanism 60 to be later described. Instead of the customary arch for carrying the front wall, and such weight of the boiler and its contents as said front wall receives, I provide one or more structural iron or steel members 7, in 65 this instance shown as steel T beams, which support the wall 5 and which rest upon the side walls and transmit the load thereto in the direction of their strength, that is vertically. This construction has a material ad- 70 vantage over either the flat or springing arch in that there is no horizontal thrust exerted against the side walls.

I protect the lower faces of the member or members 7 from the heat of the fire by fire-brick 8 which are mounted on doors 9. These doors, of which there are two, (one being open in Fig. 2) have a front plate 10 of sufficient width to cover the brick of arch 5 below the front plate 6 and to extend down and 80 form the front of a water cooled chamber 11 which extends the full width of the door. The metal walled chamber 11, aside from forming a support for the fire-brick 8, serves to protect the brick from the abrasive action 85 of the fuel as it passes from the hopper on to the grate.

The doors are mounted on hinges 12, 13 bolted thereto and provided with orifices to receive hinge pins 14, 15 bolted on the 90 front plate 6. The hinge pin 15 is threaded and provided with a nut 16. By turning the nut 16 the position of the door may be vertically adjusted to adjust the space between the door 9 and the traveling grate. It will 95 be understood, of course, that the bricks 8 must be changed when the position of the doors is adjusted, to provide brick of proper size to reach to and protect the metal parts 7. The doors are shown in their highest position in Fig. 2. Supports 121 of adjustable length aid in carrying the weight of the doors.

Water is supplied to the water cooled chambers 11 through pipe 17 and is drawn 100 off through pipe 18. These pipes are pro-

vided with swivel connections 20, 21 to permit the opening and closing of the doors 9, and with flexible connections 22, 23 to permit of the vertical adjustment of the doors and the pipes carried thereby. I prefer to employ boiler feed water for cooling the doors thus preheating said feed water and increasing the efficiency of the boiler.

The fire-brick 8, of which any number 10 may be employed but of which three are shown for each door, are provided with a shoulder 24 to fit over the chamber 11, and with apertures 241 to receive bolts 25 having nuts 26 to fasten the brick to the front 15 plate of the door. After the brick are fastened in place the cavity 27 may be filled with clay or like material. Grooves 130 in the sides of the brick 8 receive corresponding ridges 131 on adjacent brick, thus locking 20 the brick more securely in position.

The fire-brick 8 are beveled toward the rear giving a slight incline to the lower surface of the ignition arch 100, as clearly shown in Figs. 1 and 3. It is through the 25 narrow space between the fuel bed and this ignition arch 100 that the carbon and gases released on ignition must pass and it is here that they are consumed.

A fuel hopper 28 is removably attached 30 to the furnace front by inclined fingers 29 entering ears 30 bolted to said front. Openings 32 are provided in the hopper sides to accommodate the water pipes 17 and 18.

I have illustrated my furnace as used in 35 connection with an endless traveling grate stoker 33, the specific structure of which however, forms no part of the present invention. This grate travels over front sprockets 34 and is provided with the actuating mechanism 36, 37, 38 and tension regulating devices 39 all as fully described and claimed in my prior application above referred to. Forced draft for the furnace is supplied by the blast pipe 40 which is located, as clearly shown in Fig. 1, below the 45 upper run of the grate and a little forward of the ignition arch 100. The position of this blast pipe is of importance as it is so located that ignition of the coal takes place 50 as soon as it passes under the water cooled chamber 11. The free carbon, carbon mon-oxid, and hydrocarbons, liberated in the first stages of combustion, are thus com- 55 pelled to pass through the constricted pas- sage between the highly heated ignition arch and the glowing bed of fuel. At the tem- perature to which they are thus subjected the gases and free carbon are totally ox- 60 idized, due to the excess oxygen of the blast, smoke is prevented, and all the high heat units resulting from such complete combus- 65 tion are utilized. My furnace front is also especially adapted for use with mechanical stokers of the type indicated, for the reason 65 that in devices of this character it is highly

essential that the bed of fuel be of uniform depth in its entire breadth in order that combustion may proceed at the same rate throughout the breadth of the furnace. This cannot be secured with a springing arch even 70 though other devices to spread the fuel be employed. With the forms of flat arches heretofore employed, successful results could not be obtained for the reason that the side walls are not sufficiently strong to withstand 75 the lateral thrust of a long flat arch in which the stresses are largely horizontal, and also for the reason that in such arches the bricks will work loose through repeated heating and cooling. The combination of a 80 flat arch supported on structural iron beams, with the beams protected from the fire, obviates the objections noted above to both the springing and flat arches, and the doors, aside from providing a convenient means of 85 protecting the flat arch, furnish convenient access to the interior of the furnace for purposes of repair or firing.

Having thus described my invention, what I claim is:

1. In a furnace, a front wall, a flat arch carrying the front wall, and an ignition arch below the flat arch and mounted to swing thereunder.

2. In a furnace, a front wall, a flat arch carrying the front wall, horizontally swinging doors, and an ignition arch carried by said doors in position to protect the flat arch when the doors are closed.

3. In a furnace, a grate, a front wall, a flat arch carrying the front wall, and an ignition arch mounted to swing below the front wall and into operative position above said grate.

4. In a furnace, a grate, a front wall, a flat arch carrying the front wall, horizontally swinging doors, and an ignition arch, mounted on said doors above said grate, in position to protect the flat arch when the doors are closed.

5. In a furnace, a front wall, an arch supporting said front wall, a grate, a pair of vertically adjustable doors mounted above said grate and in position to swing under said arch, each door having a water-cooled fuel-distributing front plate, and fire brick bolted to said door and resting on said water-cooled front plate.

6. In a furnace, side walls, a front wall, iron beams resting on the side walls and supporting the front wall, in combination with doors mounted to swing under the front wall and carrying an ignition arch in position to cover and protect the iron beams when the door is closed.

7. In a furnace, side walls, a front wall supporting means resting on the side walls and supporting the front wall, in combination with doors mounted to swing under the front wall and carrying an ignition arch in

position to protect the said supporting means from the heat of the fire when the doors are closed.

8. In a furnace, side walls, a front wall, structural iron beams resting on the side walls and supporting the front wall, in combination with doors mounted one on each side wall to swing on vertical axes, water-cooled chambers carried at the lower extremities of said doors, fire bricks bolted to said doors and resting on said water-cooled chambers, said doors being so located and

said fire-bricks so shaped that when the doors are closed the fire-bricks form an ignition arch above the fire and also serve to 15 protect the structural iron beams from the heat of the fire.

In testimony whereof, I hereunto affix my signature in the presence of two witnesses.

HARVEY ISERMAN.
